UNITED STATES PATENT OFFICE

CARL JAMES PETERSEN, OF BROOKLYN, NEW YORK

DISH WASHING APPARATUS

Application filed January 29, 1929. Serial No. 335,783.

This invention relates to a dish washing apparatus which is designed for attachment to the faucet of a kitchen sink and which receives its operating power from the force of the water discharged through the faucet.

Broadly, the invention comprehends a water power driven rotary mop adapted for rapid rotation in contact with the dishes while subjected to a spraying action of a portion of the water from the faucet after the same has initially expended its power to turn the mop.

The invention further comprehends a water power driven rotary mop which is mounted for free gravitational engagement with the dishes so that the weight of the mop element and its component parts exert the proper wiping pressure on the dishes.

As a still further object, the invention aims to provide an improved mop which is radially contractible and expandable to adapt the same for use respectively with cups, glasses and similar small diameter table ware and with dishes, plates or other larger diameter table ware.

As a still further specific feature of the invention, a mop is provided which includes radially adjustable arms having depending strands with means extending below the arms for engagement with the dishes to prevent contact of the arms therewith while permitting the strands to have a wiping engagement with the surface.

The invention further embodies an adjustable faucet attaching bracket, by virtue of which the device may be associated with faucets of various types.

Other features of the invention reside in the simplicity of construction and mode of use of the device, the economy with which it may be constructed, the facility with which it may be attached and removed and the general efficiency derived therefrom.

With the above recited and other objects in view, reference is had to the following description and accompanying drawings, in which there is exhibited one example or embodiment of the invention, while the claims define the actual scope of the same.

In the drawings—

Figure 1 is a perspective view of the

device in applied position to a faucet, and illustrating the mop radially expanded for operation upon plates or dishes of large diameter.

Figure 2 is a transverse sectional view 55 through the water motor.

Figure 3 is a detail sectional view illustrating the attaching bracket, taken approximately on the line 3—3 of Figure 1.

Figure 4 is a perspective view of the rotary 60 mop in its contracted condition for washing cups, glasses or similar small diameter table ware.

Figure 5 is a vertical transverse sectional view therethrough taken approximately on 65 the line 5—5 of Figure 4.

Figure 6 is a detail horizontal sectional view taken approximately on the line 6—6 of Figure 5.

Referring to the drawings by characters of 70 reference, the water motor includes a substantially cylindrical water wheel housing 10 which is provided with an upstanding tangential inlet nipple 11 which carries an elastic connecting element 12 adapted to snugly 75 fit the outlet end of the faucet A. The nipple and connecting element are formed with an internal bushing 13 provided with a downwardly extending frusto-conical bore 14. Within the housing 10 a water wheel is ar- 80 ranged consisting of a hub 15 secured onto a transverse shaft 16, said hub being provided with radially projecting circumferentially spaced blades 17 adapted to receive the impact force of the water discharged from the 85 faucet A through the connecting element 12 and inlet nipple 11. It is, of course, understood that due to the frusto-conical bore 14, the velocity of the water discharged against the blade is increased, thereby increasing the 90 force applied to the water wheel. The water wheel shaft 16 is journaled in the walls of the housing 10, and in the present instance said shaft is disposed horizontally with one end extending through the housing and having 95 secured thereto an exteriorly disposed pinion 18. The housing 10 carries an angular bracket arm 19 at its rear side and the upper horizontal portion 20 of the bracket arm is slotted at 21. In order to provide 100

means for attaching the bracket arm to the faucet A so as to allow for adjustment, a U-shaped member 22 is employed, the terminals of the arms of which are embraced by a 5 clip 23 which is provided with an upstanding threaded shank 24 which extends through the slot 21 and receives a thumb nut 25. A substantially S-shaped bolt 26 has its terminal 27 engaging the bight 28 of the U-shaped member 22 while the reversely bent remaining portion embraces the faucet A with the threaded terminal 29 extending between the legs of the U-shaped member 22. A clip 30 10 is arranged over the threaded terminal 29 and a thumb nut 31 is applied thereto for the purpose of setting up the desired clamping action. This suspends and supports the housing 10 from the faucet. The front wall of the housing from which the gear 18 is exposed is provided with vertically spaced bearing arms 32 and 33 in which a tubular vertically disposed shaft 34 is journaled for rotation. The shaft 34 has secured thereto a gear 35 which meshes with the pinion 18 15 whereby the tubular shaft is rotated when the water wheel is turned. A mop shaft 36 extends vertically through the tubular shaft 34 and is splined thereto for rotation therewith while permitted to freely slide axially 20 with respect to the tubular shaft 34. The mop shaft 36 has detachably connected with its lower end the mopping element which includes a head 37 having vertically spaced annular upper and lower flanges 38 and 39, 25 between which a pair of semi-circular arms 40 are pivoted at 41 at diametrically opposite points for swinging movement from a position coincident with the periphery of the flanges, as illustrated in Figure 4, to a radially projected position, as illustrated in 30 Figure 1. The arms are provided with extensions 42 beyond their pivotal points 41 for a purpose to be hereafter set forth. In 35 order to provide means for locking the arms either in their contracted or expanded relations, a detent element is provided which consists of a cross-head 43 which is centrally apertured to slide vertically on the upwardly projecting stem 44 of the mop head. A 40 coiled expansion spring 45 surrounds the stem and is interposed between the cross-head and the enlarged upper end 46 of the stem 44. The cross-head is provided with depending pins 47 which are designed to project through aligned apertures 48 in the flanges 38 and 39. When the arms 40 are swung inwardly or contracted to a position to coincide with the peripheries of the flanges, the pins 47 are disposed inside of the extensions 42, as illustrated in Figures 5 and 6, but when the arms are swung outwardly the pins engage outside of the major portions of the arms, as illustrated in Figure 1 of the drawings. In order to provide means for facilitating the raising of the cross-head against

the action of the spring 45, manipulating lugs 50 are provided. The upper end of the stem 46 is provided with a socket 51 which receives the lower end of the mop shaft 36 and set screws 52 serve to retain the stem and socket in connected relation. The upper end of the mop shaft 36 is provided with a swiveled head 53, and below the head a weight 54 is secured to said shaft so that the mopping element will tend to normally gravitate downwardly. The mop arms 40 receive thereover tubular bands 55 which support the mop strands 56 and the tubular bands 55 are held in place by means of hooks 57 which engage through openings 58 at the inner ends of the mop arms. In order to prevent the mop head from gravitating into contact with the dishes B while permitting the strands only to wipe over the surfaces of the dishes, a nipple 59 depends concentrically from the head, which nipple is of considerably lesser length than the length of the strands 56. 70 75 80 85

In order to provide means for spraying the dishes with water from the faucet after the force of the same has acted upon the water wheel, the main discharge spout 60 at the lower end of the housing 10 which is directed rearwardly, is formed at its closed forward end 61 with a sprayer opening 62. This permits a portion of the water to spray onto the dishes and mop while the major portion of the discharged water is directed rearwardly against the rear surface of the sink to prevent splashing. It is, of course, obvious that when cups, glasses or similar table ware of small diameter are being washed, the arms 40 will be swung inwardly to the position illustrated in Figure 4 and the operator may grasp the swiveled knob or head 53 at the upper end for moving the mop upwardly and downwardly. 90 95 100 105 110 115 120 125 130 135

What is claimed is:

1. In a dish washing apparatus, a rotary mop, means for mounting the same for free gravitational engagement with the dishes, said mop having a head and depending strands, and means of lesser length than the mop strands to engage with the dishes for holding the head in superposed relation to the upper surface of a dish while permitting said mop strands to trail over the said surface and accommodate themselves to the varying configuration of the dish being washed. 110 115 120 125 130 135

2. In a dish washing apparatus for sinks, a rotary mopping element, means for mounting and supporting the same to depend from a sink faucet for free vertical movement with respect to the faucet, said mopping element including a head and radially adjustable mop arms pivoted to the head and having depending mop strands and means extending below the mop head and arms and disposed above the lower ends of the strands for engagement with the dishes to prevent contact of the head 130 135

and arms therewith while permitting the strands to have trailing and wiping engagement with the surfaces of the dishes.

3. In a dish washing apparatus for sinks, a
5 rotary mopping element, means for mounting and supporting the same to depend from a sink faucet for free vertical movement with respect to the faucet, said mopping element including a head and radially adjustable mop
10 arms pivoted to the head and having depending mop strands, means extending below the mop head and arms and disposed above the lower ends of the strands for engagement with the dishes to prevent contact of the head
15 and arms therewith while permitting the strands to have trailing and wiping engagement with the surfaces of the dishes and means for securing said radially adjustable arms in an extended or contracted position
20 to coincide with the size of the dish being washed.

4. In a dish washing apparatus, a rotary mop including a circular head and a pair of semi-circular arms pivotally carried by the
25 head at diametrically opposite points for opposite swinging movement to a radially extended position from a contracted position coinciding with the periphery of the mop head or vice versa.
30 5. In a dish washing apparatus, a rotary mop including a circular head, a pair of semi-circular arms pivotally carried by the head at diametrically opposite points for opposite swinging movement to a radially extended position from a contracted position coinciding with the periphery of the mop head or vice versa and a common means for releasably locking the arms respectively in their extended and contracted positions.

40 Signed at New York in the county of New York and State of New York, this 26th day of January A. D. 1929.

CARL JAMES PETERSEN.
